ABSTRACT OF THE DISCLOSURE

3-(5-nitrofuran-2-yl)-5-aminoisoxazoles having a nitrile, ester, amide or urea function in the 4-position are antibacterial agents. They are prepared through condensation of 5-nitro-2-furohydroxamoyl halide with a cyanomethyl-nitrile, a cyanomethylester, cyanomethylamide or a cyanomethylurea under basic conditions.

DETAILED DESCRIPTION

The present invention relates to substituted heterocyclic compounds, and in particular to nitrofuryl derivatives of isoxazoles and to processes for the production of these compounds.

According to the present invention, there is provided a 5-nitro-2-furyl-isoxazole having the Formula I

(I)

wherein R is a —CN, —CO.OR₁ or

grouping, the group R₁ being a straight- or branched-chain alkyl group containing from 1 to 6 carbon atoms, the alkyl group being unsubstituted or hydroxyl-, alkoxy- or halogen-substituted, a straight- or branched-chain alkenyl group containing 3 or 4 carbon atoms; or a cycloalkyl group; the group R₂ being hydrogen and the group R₃ being hydrogen, a straight- or branched-chain alkyl group containing from 1 to 12 carbon atoms, the alkyl group being unsubstituted or hydroxyl, alkoxy- or halogen-substituted, a straight- or branched-chain alkenyl group containing 3 or 4 carbon atoms, cycloalkyl, carbalkoxy the alkyl portion of which is a straight- or branched-chain alkyl group containing from 1 to 5 carbon atoms, or carbamoyl; or R₂ and R₃ together form a straight or branched alkylene chain containing from 2 to 7 carbon atoms, uninterrupted or interrupted by an oxygen, nitrogen or sulphur atom.

If R₁ or the group R₃ is alkyl, each of these groups may be, for example, methyl, ethyl, n-propyl, isopropyl, n-butyl, isobutyl, secondary butyl, tertiary butyl, n-amyl, isoamyl or n-hexyl. Alkyl groups having from 1 to 4 carbon atoms are particularly preferred. If either R₁ or R₃ is an alkyl group substituted by a halogen substituent, the halogen may be fluorine or iodine but is preferably chlorine or bromine. If either R₁ or R₃ is an alkyl group which is hydroxyl-, alkoxy- or halogen-substituted, preferably the alkyl group contains 1 or 2 halogen, alkoxy or hydroxyl substituents. If either R₁ or R₃ is an alkenyl group, this may be, for example, allyl, 2-methylallyl, 2-butanyl (crotanyl) or 3-butanyl. If either R₁ or R₃ is a cyclo alkyl

2

group, this may be, for example, cyclohexyl. If the group R₃ is a carbalkoxy group, the alkyl portion of the carbalkoxy group may be, for example, methyl, ethyl, n-propyl, isopropyl, n-butyl, isobutyl, tertiary butyl or n-amyl.

If the groups R₂ and R₃ together form an alkylene chain uninterrupted by an oxygen, nitrogen or sulphur atom, this chain may be, for example, ethylene, trimethylene, propylene, tetramethylene, methyl-substituted trimethylene, dimethyl-substituted ethylene, pentamethylene, hexamethylene, heptamethylene or dimethyl-substituted pentamethylene. If the alkylene chain is interrupted by an oxygen atom, the grouping R thus formed may be, for example, morpholinocarbonyl; if the alkylene chain formed by R₂ and R₃ together is interrupted by a nitrogen atom (preferably in the form of a grouping —NQ— where Q is hydrogen or an alkyl group having from 1 to 3 carbon atoms) or by a sulphur atom, the grouping R thus formed may be, for example, a 1-piperazinylcarbonyl- or a thiomorpholino-carbonyl grouping, respectively.

Particularly preferred compounds of the invention have the Formula I wherein R is a —CN group or is a

group R₃ being hydrogen, or a straight- or branched-chain alkyl group containing from 1 to 5 carbon atoms, unsubstituted or hydroxy-substituted or R₂ and R₃ together forming a straight- or branched alkylene chain having from 2 to 7 carbon atoms uninterrupted or interrupted by an oxygen, nitrogen or sulphur atom.

The invention also provides a process of producing a 5-nitro-2-furyl-isoxazole of Formula I, which comprises reacting a 5-nitro-2-furohydroxamoyl halide having the

35 Formula II

(II)

wherein X represents a halogen atom, with a reactive methylene compound having the Formula III

(III)

wherein Y represents hydrogen or an alkali metal and R has the previous significance. The reaction between the 5-nitro-2-furohydroxamoyl halide and the reactive methylene compound of Formula III is conveniently carried out in the presence of a basic condensation promotor, preferably sodium methoxide.

The reactive methylene compound of Formula III used in the reaction may be the compound having the formula NC—CH₂—R or a corresponding reactive alkali metal derivative, preferably the sodium derivative, having the formula NC—CH(M)—R wherein M is an alkali metal.

The 5-nitro-2-furohydroxamoyl halide of Formula II is preferably the chloride or bromide. The halides may be prepared by conventional methods: the chloride may be obtained, for instance, by the method described by Doyle, Hanson, Long and Nayler in the Journal of the Chemical Society (1963) at page 5845 or by that described in Helvetica Chimica Acta (1963) volume 46 at page 1067. The halide used as starting material in the process of the invention may be a purified product or it may be the crude product so prepared, if desired, after partial purification.

The reactive methylene compound of Formula III may be, for instance, malononitrile, cyanoacetamide or an N-substituted cyanoacetamide; or an ester of cyanoacetic acid. Examples of preferred reactive methylene com-

pounds are given in the following table in which the appropriate R substituents of Formula III are stated.

Compound:	R
Malononitrile	CN
Cyanoacetamide	CONH ₂
Cyanoacetylpyrrolidine	CO.NCH ₂ CH ₂ CH ₂ CH ₂
β - (N - cyanoacetylamino)-ethanol	CO.NH.CH ₂ CH ₂ OH
Methyl cyanoacetate	COOCH ₃
Ethyl cyanoacetate	COOC ₂ H ₅
Isopropyl cyanoacetate	COO <i>i</i> -C ₃ H ₇
Allyl cyanoacetate	COOC ₃ H ₅
N-allyl cyanoacetamide	CONHC ₃ H ₅
Cyanoacetyl urea	CONHCONH ₂
β - Chloroethyl cyanoacetate	COOCH ₂ CH ₂ Cl

The present invention also provides a second process of producing a 5-nitro-2-furyl-isoxazole of Formula I wherein R represents the —CN grouping, which comprises dehydrating the corresponding 5 - nitro - 2-furyl-isoxazole of Formula I wherein R represents the

grouping.

The dehydration may be carried out, for example, by heating at an elevated temperature, preferably at a temperature in the range of from 50° C. to the boiling point of the reaction mixture under reflux. The process is preferably carried out in the presence of a conventional agent for dehydrating carbamoyl compounds to the corresponding nitriles, for instance phosphorus oxychloride.

Although the compounds of the present invention have been ascribed the Formula I above, they may also be represented by either or both of the following tautomeric Formulae IA and IB, and any specific compound of the invention may occur in any of these tautomeric forms or as a mixture of two or all thereof.

In this specification, however, the compounds are regarded for purposes of clarity as having the Formula I and are thus described and exemplified as being nitro-furyl-isoxazole derivatives.

The compounds of the invention have useful pharmaceutical and, in particular, antimicrobial properties, being valuable antibacterial, antifungal, antiviral, anthelmintic, coccidiostatic or growth-promoting agents for external or internal pharmaceutical uses.

The novel compounds according to the invention have been found to exhibit outstanding antimicrobial activities, in particular antibacterial activity. In living organisms they are active, for example, against general *Staphylococcal* infections and infections due to *Salmonella* and *Escherichia coli* species.

The following compounds have been demonstrated to be effective as bacteriostatic agents against *Staphylococcus aureus*, *Escherichia coli*, and *Mycobacterium tuberculosis* (isonicotinoyl hydrazide resistant and streptomycin resistant strains):

The compounds are particularly valuable in the treatment of infections of the intestinal or urinary tract. The compounds may also be used to protect an organic material susceptible to bacterial, fungal or other microbial

deterioration by contacting with, impregnation in or otherwise treating the material with the compounds.

Accordingly, the invention also provides a composition comprising an antimicrobially effective proportion of a 5-nitro-2-furyl-isoxazole of Formula I and a pharmacologically acceptable solid carrier or liquid diluent.

The pharmaceutical compositions according to the invention contain at least one compound of general Formula I as active substance together with a conventional pharmaceutical carrier. The type of carrier actually used depends to a great extent on the intended application: for external use, for example in disinfecting healthy skin, disinfecting wounds and in treating dermatoses and afflictions of the mucous membranes caused by bacteria ointments, powders and tinctures are used in particular. The ointment bases may be anhydrous, for instance they can consist of mixtures of wool fat and soft paraffin, or they can consist of aqueous emulsion in which the active substance is suspended. Suitable carriers for powders are, for instance, rice starch and other starches; the bulk weight of the carriers may be made lighter, if desired, for example by adding highly dispersed silicic acid, or may be made heavier by adding talcum. The tinctures may contain at least one active ingredient of the Formula I in aqueous ethanol, in particular 45% to 75% ethanol, to which 10% to 20% of glycerol may be added, if desired. Solutions prepared from polyethylene glycol and other conventional solubility promoters, and also optionally, from emulsifying agents, may be used with particular advantage in disinfecting healthy skin. The content of active ingredient in pharmaceutical compositions for external application is preferably in the range of from 0.1% to 5%.

Gargles or concentrates for their preparation, and tablets for slow dissolution in the mouth, are suitable for the disinfection of the mouth and throat. The former are preferably prepared from alcoholic solutions containing 1% to 5% of active substance to which glycerol or flavourings may be added. Lozenges, that is solid dosage units, preferably have a relatively high content of sugar or similar substances and a relatively low content of active substance, for instance 0.2% to 20% by weight, as well as the usual conventional additives such as binding agents and flavourings.

Solid dosage units, in particular tablets, dragees (sugar coated tablets) and capsules, are convenient for use in intestinal disinfection and for the oral treatment of urinary tract infections. These units preferably contain from 10% to 90% of the compounds of the general Formula I to enable the administration of daily doses of from 0.1 to 2.5 grams to adults, or of suitable reduced doses to children, to be made. Tablets and dragee cores are produced by combining the compounds of the general Formula I with solid, pulverulent carriers such as lactose, saccharose, sorbitol, maize starch, potato starch or amylopectin, cellulose derivatives or gelatines, preferably with the addition of lubricants such as magnesium or calcium stearate or polyethylene glycols of suitable molecular weight. Dragee cores may then be coated, for example with concentrated sugar solutions which can also contain gum arabic, talcum and/or titanium dioxide, or they may be coated with a lacquer dissolved in volatile organic solvents or mixture of solvents. Dyestuffs can be added to these coatings, for instance to differentiate between varying dosages. Soft gelatine capsules and other closed capsules consist, for example, of a mixture of gelatines and glycerol and may contain, for example, mixtures of the compound of Formula I with polyethylene glycol. Hard gelatine capsules contain, for example, granulates of an active substance with solid pulverulent carriers, for instance lactose, saccharose, sorbitol, mannitol, starches (such as potato starch, maize starch or amylopectin), cellulose derivatives of gelatines, and magnesium stearate or stearic acid.

In all forms for administration, compounds of the

general Formula I can be present as sole active ingredients or they can also be combined with other known pharmacologically active, and especially antibacterial and/or antimycotically or other antimicrobially active substances, for example to broaden the range of application. They can be combined for example, with 5,7-dichloro-2-methyl-8-quinolinol or other derivatives of 8-quinolinol, with sulfamerazine or sulfafurazole or other derivatives of sulfanilamide, with chloramphenicol or tetracycline or other antibiotics, with 3,4',5-tribromosalicylanilide or other halogenated salicylanilides, with halogenated carbamides, with halogenated benzoxazoles or benzoxazolones, with polychlorohydroxy-diphenylmethanes, with halogen-dihydroxy-diphenyl sulphides, with 4,4'-dichloro-2-hydroxy-diphenylether or 2',4,4'-trichloro-2-hydroxydiphenylether or other polyhalogen-hydroxydiphenylethers, or with bactericidal quaternary compounds or with certain dithiocarbamic acid derivatives such as tetramethylthiuram disulphide. Also, carriers which themselves have favourable pharmacological properties may be used, for instance sulphur as powder base or zinc stearate as a component of ointment bases.

The invention also provides a method of protecting an organic material susceptible to bacterial, fungal or other microbial attack which comprises treating the material with a 5-nitro-2-furyl-isoxazole of Formula I. The organic material may be, for instance, a natural or synthetic polymeric material, a proteinaceous or carbohydrate substance, or a natural or synthetic fibre or textile material formed therefrom.

The following examples further illustrate the present invention. The temperatures are given in degrees centigrade.

EXAMPLE 1

A solution of 1.15 g. of metallic sodium dissolved in 20 ml. of anhydrous methanol was added slowly to a mixture of 9.5 g. of 5-nitro-2-furohydroxamoylchloride and 3.3 g. of malononitrile dissolved in 80 ml. of anhydrous methanol at 20° to 25°.

After allowing to stand, the crystalline precipitate was collected, washed with water and recrystallised from a mixture of water and dimethylformamide. The product was 3-(5'-nitrofuryl-2')-4-cyano-5-amino-isoxazole, having melting point 263° with decomposition.

EXAMPLE 2

The procedure described in Example 1 was carried out using the molecular equivalent of cyanacetamide as starting material instead of the malononitrile, the reaction conditions being otherwise essentially the same.

The product was 3-(5'-nitrofuryl-2')-4-carbamoyl-5-amino-isoxazole, having melting point 212° with decomposition.

EXAMPLE 3

A solution of 1.15 g. of metallic sodium dissolved in 20 ml. of anhydrous methanol was added slowly to a mixture of 9.5 g. of 5-nitro-2-furohydroxamoylchloride and 7.6 g. of 1-cyanoacetylpyrrolidine dissolved in 120 ml. of anhydrous methanol at 20° to 25°.

After allowing to stand, the crystalline precipitate was collected, washed with water and recrystallised from a mixture of water and dimethylformamide.

The product was 3-(5'-nitrofuryl-2')-4-pyrrolidinocarbonyl-5-amino-isoxazole, having melting point 186°.

The 1-cyanoacetylpyrrolidine used as reactant in the process of Example 3 was prepared by the following method:

A mixture of 113 g. of ethyl cyanoacetate and 71 g. of pyrrolidine was heated at 110° in a distillation apparatus until the distillation of liberated alcohol ceased. After cooling, the residue was recrystallised from ethyl acetate. The product was 1-cyanoacetylpyrrolidine, having melting point 70°.

EXAMPLE 4

The procedure described in Example 3 was carried out using the molecular equivalent of 1-cyanoacetylpyrrolidine as starting material instead of the 1-cyanoacetylpyrrolidine, the reaction conditions being otherwise essentially the same.

The product was 3-(5'-nitrofuryl-2')-4-piperidinocarbonyl-5-amino-isoxazole, having melting point 188° with decomposition.

EXAMPLE 5

The procedure described in Example 3 was carried out using the molecular equivalent of ethyl cyanoacetylcarbamate as starting material instead of 1-cyanoacetylpyrrolidine, the reaction conditions being otherwise essentially the same.

The product was 3-(5'-nitrofuryl-2')-4-ethoxycarbonylcarbamoyl-5-amino-isoxazole, having melting point 218° with decomposition.

EXAMPLE 6

A solution of 2.3 g. of metallic sodium dissolved in 40 ml. of anhydrous ethanol was added slowly to a mixture of 19.1 g. of 5-nitro-2-furohydroxamoyl chloride and 11.3 g. of ethyl cyanoacetate dissolved in 120 ml. of anhydrous ethanol at 20° to 25°.

After allowing to stand, the crystalline precipitate was collected, washed with water and recrystallised from a mixture of water and dimethylformamide.

The product was 3-(5'-nitrofuryl-2')-4-ethoxycarbonyl-5-amino-isoxazole, having melting point 200°.

EXAMPLE 7

The procedure described in Example 3 was carried out using the molecular equivalent of N-cyanoacetylmorpholine as starting material instead of the 1-cyanoacetylpyrrolidine, the reaction conditions being otherwise essentially the same.

The product was 3-(5'-nitrofuryl-2')-4-morpholino-carbonyl-5-amino-isoxazole, having melting point 245° with decomposition.

EXAMPLE 8

The procedure described in Example 3 was carried out using the molecular equivalent of cyanoacetyl urea as starting material instead of 1-cyanoacetylpyrrolidine, the reaction conditions being otherwise essentially the same.

The product was 3-(5'-nitrofuryl-2')-4-ureidocarbonyl-5-amino-isoxazole having melting point 208° with decomposition.

EXAMPLE 9

The procedure described in Example 3 was carried out using the molecular equivalent of β -(N-cyanoacetyl-amino)-ethanol as starting material instead of 1-cyanoacetylpyrrolidine, the reaction conditions being otherwise essentially the same.

The product was 3-(5'-nitrofuryl-2')-4-(β -hydroxyethyl-carbamoyl)-5-amino-isoxazole, having melting point 209° with decomposition.

EXAMPLE 10

A mixture of 15 g. of 3-(5'-nitrofuryl-2')-4-carbamoyl-5-amino-isoxazole and 40 g. of phosphorus oxychloride was heated at 100° for 2 hours. After cooling, 100 ml. of water were added slowly to the mixture with further cooling and the precipitate was collected, washed with water and recrystallised from a mixture of water and dimethylformamide.

The product was 3-(5'-nitrofuryl-2')-4-cyano-5-amino-isoxazole, having melting point 263° with decomposition, identical with the product obtained in Example 1.

EXAMPLE 11

A solution of 2.3 g. of metallic sodium dissolved in 40 ml. of anhydrous methanol was added slowly to a mix-

ture of 19.1 g. of 5-nitro-2-furohydroxamoyl chloride and 9.9 g. of methyl cyanoacetate dissolved in 120 ml. of anhydrous methanol at 20° to 25°.

After allowing to stand, the crystalline precipitate was collected, washed with water and recrystallised from a mixture of water and dimethylformamide.

The product was 3-(5'-nitrofuryl-2')-4-methoxycarbonyl-5-amino-isoxazole having melting point 240° with decomposition.

EXAMPLE 12

The procedure described in Example 11 was carried out using the molecular equivalent of isopropylcyanoacetate as starting material instead of the methyl cyanoacetate, the reaction conditions being otherwise essentially the same.

The product was 3-(5'-nitrofuryl-2')-4-isopropoxycarbonyl-5-amino-isoxazole having melting point 174°.

EXAMPLE 13

The procedure described in Example 11 was carried out using the molecular equivalent of allyl cyanoacetate as starting material instead of methyl cyanoacetate, the reaction conditions being otherwise essentially the same.

The product was 3-(5'-nitrofuryl-2')-4-allyloxycarbonyl-5-amino-isoxazole having melting point 124°.

EXAMPLE 14

The procedure described in Example 11 was carried out using the molecular equivalent of cyclohexyl cyanoacetate as starting material instead of the methyl cyanoacetate, the reaction conditions being otherwise essentially the same.

The product was 3-(5'-nitrofuryl-2')-4-cyclohexyloxy carbonyl-5-amino-isoxazole having melting point 170°.

Similarly, by using n-hexyl cyanoacetate instead of the methyl cyanoacetate, the product obtained is 3-(5'-nitrofuryl-2')-4-(n-hexyloxycarbonyl)-5-amino-isoxazole, having melting point 185° to 187°.

EXAMPLE 15

The procedure described in Example 11 was carried out using the molecular equivalent of N-methylcyanoacetamide as starting material instead of the 1-cyanoacetylpyrrolidine, the reaction conditions being otherwise essentially the same.

The product was 3-(5'-nitrofuryl-2')-4-methyl-carbamoyl-5-amino-isoxazole having melting point 238° with decomposition.

EXAMPLE 16

The procedure described in Example 11 was carried out using the molecular equivalent of N-ethylcyanoacetamide as starting material instead of the 1-cyanoacetylpyrrolidine, the reaction conditions being otherwise essentially the same.

The product was 3-(5'-nitrofuryl-2')-4-ethylcarbamoyl-5-amino-isoxazole having melting point 206° with decomposition.

EXAMPLE 17

The procedure described in Example 11 was carried out using the molecular equivalent of N-allylcyanacetamide as starting material instead of the 1-cyanoacetylpyrrolidine, the reaction conditions being otherwise essentially the same.

The product was 3-(5'-nitrofuryl-2')-4-allylcarbamoyl-5-amino-isoxazole having melting point approximately 220°.

EXAMPLE 18

By carrying out the procedure described in Example 3 using the molecular equivalent of any of the following amine reactants as starting material instead of the 1-cyanoacetylpyrrolidine there used:

N-cyanoacetylaminon-propanol
N-cyanoacetyl-β-bromo-ethylamine

the reaction conditions being otherwise the same, the following products are obtained respectively: 3-(5'-nitrofuryl-2')-4-γ-hydroxypropylcarbamoyl-5-amino-isoxazole, 3-(5'-nitrofuryl-2')-4-β-bromoethylcarbamoyl-5-amino-isoxazole.

EXAMPLE 19

By carrying out the procedure described in Example 5, using the molecular equivalent of methyl cyanoacetylcarbamate, isopropyl cyanoacetylcarbamate or n-amyl cyanoacetylcarbamate, instead of the ethyl cyanoacetylcarbamate there used, the reaction conditions being otherwise essentially the same, 3-(5'-nitrofuryl-2')-4-(methoxycarbonylcarbamoyl)-5-amino-isoxazole, 3-(5'-nitrofuryl-2')-4-(isopropoxycarbonylcarbamoyl)-5-amino-isoxazole or 3-(5'-nitrofuryl-2')-4-(n-amyoxy carbonylcarbamoyl)-5-amino-isoxazole, is obtained respectively.

EXAMPLE 20

By carrying out the procedure described in Example 3 using the molecular equivalent of any of the following amines instead of the 1-cyanoacetylpyrrolidine there used:

1-cyanoacetyl-ethylpiperidine
1-cyanoacetyl-thiomorpholine

the reaction conditions being otherwise essentially the same, the following products are obtained, respectively: 3-(5'-nitrofuryl-2')-4-ethylpiperidinocarbonyl-5-amino-isoxazole, 3-(5'-nitrofuryl-2')-4-thiomorpholinocarbonyl-5-amino-isoxazole.

EXAMPLE 21

The procedure described in Example 11 was carried out using the molecular equivalent of tertiary butyl cyanoacetate as starting material instead of the methyl cyanoacetate, the reaction conditions being otherwise essentially the same.

The product was 3-(5'-nitrofuryl-2')-4-(tertiarybutoxy carbonyl)-5-amino-isoxazole having melting point 171°.

EXAMPLE 22

The procedure described in Example 11 was carried out using the molecular equivalent of β-chloroethyl cyanoacetate as starting material instead of the methyl cyanoacetate, the reaction conditions being otherwise essentially the same.

The product was 3-(5'-nitrofuryl-2')-4-(β-chloroethoxy carbonyl)-5-amino-isoxazole, having melting point initially at 152° following by resetting with subsequent melting at 158°.

Similarly by using the molecular equivalent of any of the following cyanoacetates instead of the β-chloroethyl cyanoacetates:

β-chloropropyl cyanoacetate
γ-chloropropyl cyanoacetate
β-bromoethyl cyanoacetate
n-propyl cyanoacetate
isobutyl cyanoacetate
secondary-butyl cyanoacetate
ω-hydroxy-n-hexyl cyanoacetate

60 δ-hydroxy-n-butyl cyanoacetate
β-methoxy-ethyl cyanoacetate

the following products are obtained, respectively:

3-(5'-nitrofuryl-2')-4-(β-chloropropoxy-carbonyl)-5-aminoisoxazole,
3-(5'-nitrofuryl-2')-4-(γ-chloropropoxy-carbonyl)-5-amino-isoxazole having melting point 158°,
3-(5'-nitrofuryl-2')-4-(β-bromoethoxy-carbonyl)-5-amino-isoxazole,

70 3-(5'-nitrofuryl-2')-4-(n-propoxy-carbonyl)-5-amino-isoxazole having melting point 186°,
3-(5'-nitrofuryl-2')-4-(isobutoxy-carbonyl)-5-amino-isoxazole having melting point 175°,
3-(5'-nitrofuryl-2')-4-(secondary-butoxy-carbonyl)-5-amino-isoxazole having melting point 126°,

9

- 3-(5'-nitrofuryl-2')-4-(ω -hydroxy-n-hexyloxy-carbonyl)-5-amino-isoxazole,
 3-(5'-nitrofuryl-2')-4-(δ -hydroxy-n-butoxy-carbonyl)-5-amino-isoxazole,
 3-(5'-nitrofuryl-2')-4-(β -methoxy-ethoxy-carbonyl)-5-amino-isoxazole.

EXAMPLE 23

By carrying out the procedure described in Example 3 using the molecular equivalent of any of the following amine reactants as starting material instead of the malononitrile there used:

- N-cyanoacetyl-sec-octylamine
 N-cyanoacetyl-n-dodecylamine
 N-cyanoacetyl-cyclohexylamine
 N-cyanoacetyl- β -bromoethylamine
 N-cyanoacetyl- γ -methoxypropylamine
 N-cyanoacetyl- γ -isopropoxypropylamine

the reaction conditions being otherwise the same, the following products are obtained respectively:

- 3-(5'-nitrofuryl-2')-4-sec-octylcarbamoyl-5-amino-isoxazole,
 3-(5'-nitrofuryl-2')-4-n-dodecylcarbamoyl-5-amino-isoxazole,
 3-(5'-nitrofuryl-2')-4-cyclohexylcarbamoyl-5-amino-isoxazole,
 3-(5'-nitrofuryl-2')-4- β -bromoethylcarbamoyl-5-amino-isoxazole,
 3-(5'-nitrofuryl-2')-4- γ -methoxypropylcarbamoyl-5-amino-isoxazole,
 3-(5'-nitrofuryl-2')-4- γ -isopropoxypropylcarbamoyl-5-amino-isoxazole.

These compounds, their functional derivatives, or mixture of any two or more thereof may be formulated in a conventional manner with pharmacologically acceptable solid carriers or liquid diluents.

We claim:

1. A compound of the formula:

wherein

R is —CN, —COOR₁, or

in which

R₁ is alkyl of 1 to 6 carbon atoms which is unsubstituted or substituted by hydroxy, halo or alkoxy of from 1 to 4 carbon atoms; alkenyl of 3 or 4 carbon atoms; or cycloalkyl of from 5 to 7 carbon atoms; and

R₂ is hydrogen;

R₃ is hydrogen; alkyl of from 1 to 12 carbon atoms which is unsubstituted or substituted by hydroxy, halo or alkoxy of from 1 to 4 carbon atoms; alkenyl of 3 or 4 carbon atoms; alkoxy carbonyl on which the alkoxy group has from 1 to 5 carbon atoms; or carbamoyl; or

R₂ and R₃ taken together, together with the nitrogen atom to which they are attached are pyrrolidino, piperidino, morpholino, thiomorpholino, piperazine or 4-lower alkylpiperazino.

2. A compound according to claim 1 wherein R is —COOR₁.

3. A compound according to claim 2 wherein R₁ is alkyl of 1 to 5 carbon atoms.

10

4. A compound according to claim 2 where R₁ is alkyl of 1 to 5 carbon atoms, substituted hydroxy, chloro or fluoro.

5. A compound according to claim 1 wherein R is

- 10 6. A compound according to claim 5 wherein R₂ is hydrogen and R₃ is alkyl of 1 to 5 carbon atoms which is unsubstituted or substituted by hydroxy.

7. A compound of the formula

- 15 20 wherein R is cyano, carboxamido or carb(lower alkoxy).

8. A compound as defined in claim 1 which is 3-(5'-nitrofuryl-2')-4-cyano-5-amino-isoxazole.

9. A compound as defined in claim 1 which is 3-(5'-nitrofuryl-2')-4-carbamoyl-5-amino-isoxazole.

- 25 10. A compound as defined in claim 1 which is 3-(5'-nitrofuryl-2')-4-pyrrolidinocarbonyl-5-amino-isoxazole.

11. A compound as defined in claim 1 which is 3-(5'-nitrofuryl-2')-4-piperidinocarbonyl-5-amino-isoxazole.

12. A compound as defined in claim 1 which is 3-(5'-30 nitrofuryl-2')-4-(ethoxycarbonyl-carbamoyl) - 5 - amino-isoxazole.

13. A compound as defined in claim 1 which is 3-(5'-nitrofuryl-2')-4-ethoxycarbonyl-5-amino-isoxazole.

- 35 14. A compound as defined in claim 1 which is 3-(5'-nitrofuryl-2')-4-morpholinocarbonyl-5-amino-isoxazole.

15. A compound as defined in claim 1 which is 3-(5'-nitrofuryl-2')-4-ureidocarbonyl-5-amino-isoxazole.

16. A compound as defined in claim 1 which is 3-(5'-nitrofuryl-2')-4-(β -hydroxyethyl-carbamoyl) - 5 - amino-isoxazole.

- 40 17. A compound as defined in claim 1 which is 3-(5'-nitrofuryl-2')-4-methoxycarbonyl-5-amino-isoxazole.

18. A compound as defined in claim 1 which is 3-(5'-nitrofuryl-2')-4-isopropoxycarbonyl-5-amino-isoxazole.

- 45 19. A compound as defined in claim 1 which is 3-(5'-nitrofuryl-2')-allyloxycarbonyl-5-amino-isoxazole.

20. A compound as defined in claim 1 which is 3-(5'-nitrofuryl-2') - 4 - cyclohexyloxycarbonyl - 5 - amino-isoxazole.

- 50 21. A compound as defined in claim 1 which is 3-(5'-nitrofuryl-2')-4-methylcarbamoyl-5-amino-isoxazole.

22. A compound as defined in claim 1 which is 3-(5'-nitrofuryl-2')-4-ethylcarbamoyl-5-amino-isoxazole.

- 55 23. A compound as defined in claim 1 which is 3-(5'-nitrofuryl-2')-4-allylcarbamoyl-5-amino-isoxazole.

24. A compound as defined in claim 1 which is 3-(5'-nitrofuryl-2') - 4 - tertiarybutoxycarbonyl - 5 - amino-isoxazole.

- 60 25. A compound as defined in claim 1 which is 3-(5'-nitrofuryl-2') - 4 - (β -chloroethoxycarbonyl) - 5 - amino-isoxazole.
